MICROPHONE

Charles B. Fisher, Washington, D. C.

Application September 30, 1942, Serial No. 460,229

4 Claims. (Cl. 179—187)

This invention relates to microphones for use by busy operators within noisy vehicles, such as aircraft and tanks, and particularly towards substantially improving the resultant signal-to-noise ratio.

Attempts have been made for a considerable period to provide a practical and efficient microphone for use by aircraft pilots, tank operators, and the like, that is readily used and provides a high signal-to-noise ratio despite a noisy background. Such attempts included microphones strapped against the operator's throat, which were termed "throat microphones." The shortcomings of the throat microphones were that the intelligibility and quality of the resultant voice signals were unsatisfactory, and that generally the resultant signals were relatively weak and required extra pre-amplification. Also, the microphones were suspended before the mouth of the operator. Such were impractical since the microphone or its fixture interfered with the operator's movements, and particularly since such microphones also responded to the surrounding engine noises which were co-mingled with the voice signals, and deteriorated the resultant signal intelligibility.

In accordance with the present invention I provide a small light-weight microphone combined with a projecting stem that is placed in the mouth and gripped by the teeth. The stem contains a sound channel or passage communicating with the sensitive element of the microphone. The microphone unit is unobtrusive and in no manner interferes with the usual activities or duties of the operator. The small, light-weight microphone unit of the present invention is readily supported by the mouth, is not tiring on the operator, and does not interfere with his speaking. Most importantly, the resultant speech signals are of good quality accompanied with negligible background noise.

I have determined the sound pressure of speech, at the position within the mouth and behind the teeth, to be about the order of twice the corresponding sound pressure just outside of the mouth in front of the lips, although the distance apart is only about $\frac{1}{2}$ inch. Also, the mouth shields and otherwise greatly attenuates outside noise pressure with respect to the sensitive section of my microphone unit. Such attenuation of the outside noise is of the order of ten to one in pressure. Thus, by my invention, the higher sound pressure created within the operator's mouth is directly communicated to the microphone diaphragm through the supporting

stem. The result is an overall improvement in signal-to-noise pressure ratio of the order of at least twenty to one, or the order of twenty-six decibels. The microphone system of the invention is thus very practical in service, and produces clear voice signals of relatively greater power and signal-to-noise ratio than prior microphones.

It is accordingly an object of my present invention to provide a novel microphone arrangement that affords a substantial improvement in the resultant signal-to-noise ratio when used in noisy locations, such as in fighter planes or tanks.

Another object of the present invention is to provide a novel microphone that is readily supported by the operator's mouth in a manner so as not to interfere with his speaking.

A further object of the present invention is to provide a small lightweight microphone that is readily held in the operator's mouth, and is not subject to background noises so as to afford high signal-to-noise ratio voice signals.

These and further objects and advantages of the present invention will become more apparent in the following description of a preferred embodiment thereof, illustrated in the drawings, in which:

Fig. 1 shows the microphone unit of the invention in position in the operator's mouth; Fig. 30 2 is an enlarged horizontal cross-sectional view of the microphone unit, partly in elevation; Fig. 3 is a vertical cross-sectional view of the microphone unit, partly in elevation; Fig. 4 is a front elevational view of the microphone; and Figs. 5 35 and 6 are respective elevational and top views of the microphone stem.

The microphone unit 10 is provided with a projecting stem 11 which, as shown in Fig. 1, is adapted to be gripped between the teeth 12 by the operator. The whole unit is made small and light in weight, so as to be readily carried between the teeth, and without materially interfering with the speaking action of the operator. The tip 13 of the stem 11 is held behind the teeth 12, within the mouth cavity. A central through channel 14 within the stem 11 constitutes a sound passage between the mouth cavity, where the sounds are generated, and the sound sensitive element of the microphone 15 of unit 10. A microphone cable 16 of flexible wires electrically connects the microphone unit 10 to the amplifier or sound apparatus, which, like the circuit connections for the microphone, are conventional and are not shown.

55 The microphone unit 10 comprises a casing 17

within which is mounted the sensitive microphone element 15, as for instance a conventional carbon button, an electrodynamic microphone unit, or equivalent sound translating element for converting the sound waves conducted to it through stem 11 into corresponding electrical currents. A threaded cover plate 18 coats at 19 with casing 17 to form a closure for the microphone 15.

The stem 11 contains a shoulder at 20 that is press-fitted into an opening in casing 17 directly in front of the sensitive portion or diaphragm of the microphone element 15. The channel 14 provides a sound passage between tip 13 and microphone element 15, and terminates as a hole or outer opening at 21 in the tip. Two additional channels 22 and 23 are drilled in tip 13, transverse to the direction of channel 14, and provide four outer openings at tip 13.

The stem 11 is designed to fit comfortably in the mouth and be well supported and gripped by the teeth with the lips closed around it. The horizontal section of the stem is preferably wider than the vertical height so that the microphone is stably held in the mouth. As seen in Figs. 5 and 6, the stem is rather flat, and the tip 13 projects away from the body portion to prevent longitudinal outward displacement or slippage of the stem from the teeth.

The group of openings provided by the channels 14, 22 and 23, affords openings through which the sound pressures generated within the mouth are directly communicated to the microphone element 15. The plurality of holes at stem tip 13 insures a continuous unattenuated communication of the sound pressures from the mouth to the microphone 15, despite the possibility that the tip of the tongue may temporarily close one or more of the openings. At least some of the openings will always be exposed and provide continuous normal operation of the microphone. The stable support afforded by the preferred stem 11 permits the microphone to be readily held in position while the operator is talking in a normal manner. The upper and lower sets of teeth 12 are separated by at least about $\frac{1}{8}$ ", and the speech operation is substantially uninhibited. The projecting portions of the stem prevent it from sliding out of the mouth, and the teeth need not be gripped tightly, but held loosely thereabout somewhat in the manner of talking while smoking a pipe.

The stem 11 is preferably constructed of a composition or plastic material for strength and lightness. The material should have a neutral taste and toward this end I prefer such materials as clear cellulose acetate, a phenol formaldehyde plastic, or the like. The microphone casing 17, 18 is likewise also of a strong but light composition or plastic material. Also, I have found that sufficiently sensitive microphone elements 15 are commercially available so as to be fitted into a preferred casing of about $\frac{5}{16}$ " to $\frac{3}{4}$ " in diameter, and about $\frac{3}{8}$ " to $\frac{1}{2}$ " in thickness. The stem 11 is preferably of the order of $\frac{3}{4}$ " long from end to end, and about $\frac{5}{8}$ " wide at the widest section across tip 13, tapering down to the microphone casing 17 to a width of about $\frac{3}{8}$ ". I have found such dimensions to be practical in service, and the construction is such as to make the microphone small, light, comfortable and unobtrusive.

Also, I have found that the preferred dimensions, and the construction pursuant to the present invention, provide a microphone unit that is efficient and practical in the field. This microphone, using a carbon-button or other form of

microphone element 15, is practically unaffected by noises occurring within a tank or aircraft in military operation. The higher pressure sounds within the mouth cavity behind the teeth are directly communicated to the microphone element. Also, the lips closed about stem 11 shield the speech sound waves to the microphone element from the local parasitic noises. The overall improvement in the signal-to-noise ratio is of the order of 26 decibels as compared to a conventional microphone unit held in position directly in front of the mouth. Also, the intelligibility of the resultant sound waves reproduced by the microphone system of the present invention is superior to the open type of conventional microphones that are subjected to the background noises in service.

Although I have described a preferred embodiment and construction for the microphone of my present invention, it is to be understood that variations thereof may be practiced without departing from the broader spirit and scope of the invention as defined in the following claims.

Having thus described my invention, what I claim is:

1. A microphone of the character described comprising a casing containing a sound translating microphone element, and a stem extending from an opening in said casing, said stem having

30 a first through channel that communicates with the sound sensitive portion of said microphone element, the end tip portion of said stem being adapted to fit into one's mouth and held gripped between the teeth, and said stem having a second channel in the end tip portion thereof extending transversely of and intersecting with said first channel.

2. A microphone of the character described comprising a casing containing a sound translating microphone element, a flat stem extending from an opening in said casing, said stem having a longitudinal channel that communicates to the sound sensitive portion of said microphone element and also having a second channel in the terminal portion thereof extending transversely of said longitudinal channel.

3. A microphone of the character described comprising a casing containing a sound translating microphone element, a flat stem extending from an opening in said casing, said stem having a longitudinal through channel that communicates to the sound sensitive portion of said microphone element and having a terminal portion that fits into one's mouth when gripped between the teeth, said stem having a plurality of channels at the terminal portion thereof extending transversely of and intersecting with said longitudinal channel.

4. A microphone of the character described comprising a light-weight casing containing a sound translating microphone element, a light-weight stem extending from an opening in said casing, said stem having a first through channel that communicates with the sound sensitive portion of said microphone element, the tip of said stem being adapted to fit into one's mouth and held gripped between the teeth, said stem having a plurality of channels at said tip extending perpendicularly to and intersecting said first channel, said channels affording corresponding openings in said tip for assuring continuous sound pressure communication from the mouth to said microphone element through said first channel.

CHARLES B. FISHER.
